Primary Examiner — Rhea Shields*(74) Attorney, Agent, or Firm* — Mahamedi IP Law LLP**CLAIM**

The ornamental design for a display screen computing device with graphical user interface, as shown and described herein.

DESCRIPTION

FIG. 1 illustrates a display screen computing device with graphical user interface, according to a first embodiment; and,

FIG. 2 illustrates the display screen computing device with graphical user interface, as provided on a portion of a display screen of the computing device.

In the drawings, the broken lines are for the purpose of showing a display screen computing device with graphical user interface and forms no part of the claimed design. The broken lines showing the outlined text is provided for the purpose of illustrating portions of the graphical user interface that forms no part of the claimed design.
